UNITED STATES PATENT OFFICE.

JOHN L. MCKENZIE, OF BEECH GROVE, INDIANA, ASSIGNOR, BY DIRECT AND MESNE ASSIGNMENTS, OF ONE-FOURTH TO WILLIAM H. TRUESDELL AND ONE-HALF TO JOHN T. CLAPP, BOTH OF BEECH GROVE, INDIANA.

ENVELOP-OPENER.

1,249,441.

Specification of Letters Patent. Patented Dec. 11, 1917.

Application filed October 20, 1916. Serial No. 126,731.

To all whom it may concern:

Be it known that I, JOHN L. MCKENZIE, a citizen of the United States, residing at Beech Grove, Marion county, and State of Indiana, have invented and discovered certain new and useful Improvements in Envelop-Openers, of which the following is a specification.

My invention relates to envelop cutters and its object is to provide a machine of this kind capable of being operated with great rapidity and which leaves both hands of the operator free to insert the envelop to be opened into the machine; to provide means whereby the cutting operation of the blade is effected by power the application of which is controlled by trip mechanism adapted to be actuated by the contact of the envelop therewith; to provide means whereby the blade tripping mechanism is reset during the descent of the movable blade whereby rapidity of operation is insured; to provide such a construction of the machine that the parts may be returned to normal position either by the foot of the operator or by external power; to provide an effective form of cutting blade, and to generally improve the construction of machines of this class.

With these objects in view, my invention is illustrated in the accompanying drawings in which Figure 1 is a top plan view of the machine; Fig. 2, a front view in elevation; Fig. 3, a vertical section; Fig. 4, a horizontal section on the line 4—4 of Fig. 3 and Fig. 5, a detail vertical section on the line 5—5 of Fig. 2.

Referring to the drawings, 1 constitutes the base of the machine which is preferably made in the form of a rectangular body adapted to inclose the main operative parts. On the horizontal bed or table of the machine is mounted a fixed blade 2 which is adjusted and maintained in adjusted position on the base of the machine by means of angular, adjusting bearing plates 2' which are engaged by suitable set screws. These plates are adapted to bear against the front edge of the fixed blade. The blade is adapted to be held in position by means of set screws 2'' which engage in slots in the bed of the machine. Coöoperating with the inner cutting edge of the fixed blade is a vertically reciprocable blade 3 having preferably two inclined

shear edges 4 which meet in the center at an apex or common entering point whereby a shearing cut is imparted to the envelop on both sides of the center which enables a quicker and shorter movement of the movable blade to be provided, while at the same time a shearing cut along the entire edge of the envelop is obtained. The vertically movable blade is adapted to sever a marginal strip from the sealed envelop which strip is of a width determined by the extent of projection of the edge of the envelop beyond the fixed blade which is controlled by a trip positioned just behind the fixed blade. This trip 5 includes a bar extending entirely across the fixed blade and behind the inner edge of the latter and below the movable blade and which trip is adapted to be carried down beyond the limit of movement of the movable blade as the latter descends, by mechanism to be now described. The trip 5 may be characterized as the primary actuated trip. An adjustable bed plate 5' serves to limit the rearward swinging movement of the trip bar and consequently fixes the width of the strip to be cut.

The trip 5 is fixed to a rock shaft 6 which extends horizontally across the machine and which is journaled in the end bars 7 of a horizontal rocking frame including a cross bar 7' and which frame is adapted to rock on the horizontal pivot rod 8. A weight 5'' is carried by an arm fixed to the rocking arm 6, whereby the trip bar 5 is adapted to be automatically swung back to correct position to be operated by the contact of an envelop, after each operation.

Fixed to the rocking shaft 6 is a vertically depending rod 9 which is loosely connected at its lower end by a wire link 10 with a latch lever 11. Said latch lever has a notch 11' adapted to engage the inner end of one arm 12 of a bell crank lever mounted upon a bracket projecting inwardly from the rear part of the frame of the machine and the other arm 12' of which bell crank has a projecting nose-piece 12'' which is adapted to strike against the lower end of a contact arm 14 of a pivoted trip bar 15 for the purpose of releasing the movable blade and permitting the descent of the latter as hereinafter described. A spiral spring 13 connected at one end to the rigid frame of the machine

- and at the other end to the arm 12 of the bell crank lever serves to actuate said lever and carry it forcibly against the lower end of the contact arm 14 when said bell crank member 5 12 is released from the latch 11. Similarly a spring 13' is connected to the latch 11 and serves to restore the same to normal engaging position after it has been actuated by the link 10.
- 10 The trip member 15 is fixed to a rocking shaft 16 pivoted in extensions 17 carried by upright standards on the frame of the machine. Fixed centrally on the rocking shaft 16 is a catch 18 having a hook at its lower 15 end adapted to engage a lug 19 secured to the upper part of the vertically movable blade 3 and which catch is adapted to hold the blade in raised position until the bar 15 has been tripped, whereupon the catch will 20 be released from the blade so as to permit the same to descend. The blade is carried rapidly and forcibly downward upon its release by means of driving springs 20, one of which is mounted at each end of the machine and the upper ends of which springs are connected to lugs 20' carried by the blade, these lugs being adapted to move between the vertical standards 20'' whereby the blade is guided in its vertical movement.
- 25 30 A flat spring 28 is secured by a notch 29 to each side of the vertical edge of the movable blade and the springs bear against the standards and serve to yieldingly guide the side edges of the blade in straight parallel 35 lines between the standards.

Fixed to the blade 3 is a re-setting member consisting of a vertical rod 21 on which is fixed a block 22 which in the descending movement of the blade and rod is adapted 40 to contact with a cross bar 23 constituting part of the horizontal rocking frame formed by the bars 7 and the arm 7'. By the contact of the block 22 with the cross bar 23, the rocking frame is operated to depress the 45 cross bar 7' into contact with the bell crank arm 12 and reengage the latter with the latch 11 so as to hold the blade releasing mechanism in engagement with the trip 5 once more and ready for the next operation 50 by the contact of the envelop with the trip. The rocking frame 7 is held normally upwardly and retracted into upward position automatically by means of springs 24 connected to the cross bar 7'. An adjustable 55 screw 25 serves as a stop for the frame and the lower end thereof is adapted to contact with the cross bar 7'.

The frame 7-7', the bell crank 12 and bar 15, constitute an intermediate or blade 60 releasing trip mechanism.

The blade is adapted to be restored to its uppermost position ready for operation, by means of the contact of a foot pedal or other lifting member (not shown) adapted to 65 bear against the lower end of the rod 21.

This restoring operation may be effected by suitable power means, if desired, although ordinarily it will be found that sufficient speed of operation may be obtained through the operation of the blade by the foot of 70 the operator.

In order to guide and guard the envelop contact bar 5 of the primary trip, back to its normal position above the level of the bed, a plate or bar 27 is mounted just below the 75 fixed blade. To the rear of the fixed blade and at the bottom of the frame 1 is a strip receiving trough 30, adapted to receive the marginal piece cut from the envelop, thereby protecting the mechanism of the machine 80 from entangling pieces of paper.

A casing or cover is mounted on the machine over the movable blade and the front wall 31 of the cover extends down to a line sufficiently near the fixed blade to prevent 85 the insertion of the fingers of the operator, thus serving as a safety guard.

The operation of the machine is as follows:-

As the envelop 26 is moved forward by 90 hand across the face of the fixed blade, its inner margin will be carried into contact with the trip bar 5 which projects a short distance above the surface of the fixed blade. The envelop will rock this trip bar back a 95 short distance on the pivot 6 until a narrow marginal strip of the envelop is projected beyond the rear edge of the fixed blade. The trip is limited in its movement by the rear bed plate and thus serves as a gage for the 100 strip to be cut. As the trip 5 is swung back, the said shaft 6 will be rocked and thereupon the arm 9 fixed thereto will be carried forwardly pulling the wire link 10 forward, against the tension of the spring 13' and carrying the latch 11 out of engagement with the arm 12 of the bell crank, whereupon the spring 13 will carry upward the arm 12 and throw the end of the arm 12' against the lower end of the contact arm 14 of the 110 trip bar 15, whereupon the rock shaft 16 will be rocked so as to carry the catch 18 out of engagement with the lug 19 fixed on the movable reciprocating blade 3. The blade 115 3 will then be instantly thrown downward by the driving springs 20 and the two shearing edges 4 of the blade will sever a marginal strip from the envelop. The spring guides 28 will insure a correct straight, vertical movement of the blade. As the blade 120 descends, the block 22 carried by the rod 21 will move down against the cross bar 23 and depress the horizontal frame 7-7' so as to carry the trip bar 5 down below the limit of travel of the blade and to 125 carry the front cross bar 7' of the frame down into engagement with the arm 12 so as to restore the engagement of the bell crank lever with the latch 11. It will thus be seen that the blade tripping mechanism 130

is reset to the position in which it is ready for another operation, during the descent of the blade. This mode of operation insures a very quick and positive resetting action as compared with resetting the trip during the return movement of the blade.

As the blade is moved up by the pressure of the foot pedal or other external power means, thus releasing the frame 7—7', the trip 5 will be permitted to rise into normal position and to swing forward, such swinging movement being effected automatically by means of the weight 5''. The trip bar is guided back to position by means of the guard plate 27.

The release and throw of the blade are almost instantaneous and consequently a very rapid operation is obtainable. Either one or a number of envelopes may be opened 20 at a single operation.

Having thus described my invention, what I claim is:

1. In an envelop opener, in combination with a fixed blade and a movable blade, a 25 combined envelop gage and trip member located adjacent the edge of the fixed blade and means for moving said member away from the movable blade as the latter descends.

30 2. In an envelop opener, in combination with a fixed blade, a vertically movable blade, power means for operating the movable blade, a combined gage and trip member adapted to be operated by the contact 35 of the envelop and located adjacent the edge of the fixed blade and below the movable blade, means permitting the rearward movement of the trip member as the envelop is advanced, means operated by such movement to release the power means, and means to carry said member away from the movable blade as the latter descends.

3. In an envelop opener, in combination with a fixed blade, a vertically movable 45 blade, power means for operating said movable blade, a combined trip and gage member mounted adjacent the fixed blade and below the movable blade and operable by the contact of the envelop, said trip member 50 being pivotally mounted on a support to swing back from the edge of the fixed blade and said support being pivotally mounted to carry the trip member bodily downward when said support is rocked.

55 4. In an envelop opener, in combination with a fixed blade, a vertically movable blade, power means for operating said movable blade, a combined gage and trip member mounted adjacent the fixed blade and 60 pivotally mounted on a rocking support and adapted to be operated by the contact of the envelop, means for automatically restoring the trip member to normal position, means for rocking said support to carry the trip 65 away from the movable blade as the latter

descends and means for automatically restoring said rocking support to its normal position.

5. In an envelop opener, in combination with a fixed blade, a vertically movable 70 blade, power means for operating said movable blade, latch means for holding the movable blade inoperative, a trip mechanism controlling said power means latch, a trip operated by the contact of the envelop, 75 means of operative connection between said contact trip and said power controlling trip and a part carried by the movable blade for resetting said latch power trip in the downward movement of the movable blade by 80 positive contact of said part with said trip mechanism.

6. In an envelop opener, in combination with a fixed blade, a vertically movable 85 blade, power means for operating said movable blade, a blade releasing trip operable to permit the operation of said power means, an envelop contact trip below the movable blade, means of connection between said contact trip and said blade releasing trip, 90 means for resetting the blade releasing trip by the blade as it descends and means for re-setting the contact trip upon the ascent of the blade.

7. In an envelop opener, in combination 95 with a vertically movable blade for severing a marginal strip from the envelop, means for forcing said blade downwardly, a catch for retaining said blade in raised position, spring operated tripping means for said 100 catch, a spring operated latch for normally retaining said tripping means in inoperative position and a trip member connected to said latch and adapted to be operated by the contact of the envelop.

8. In an envelop opener, in combination with a fixed blade, a vertically movable blade, springs for operating said blade, a catch for detaining said blade in raised position, a spring actuated trip for releasing 110 said catch, a latch for retaining said trip, a movable member for restoring said trip to engagement with said latch and means connected to the movable blade for operating said restoring member during the descent 115 of the blade.

9. In an envelop opener, in combination with a fixed blade, a vertically movable blade, springs for throwing said blade downward to sever a marginal strip from the envelop, a catch for holding said blade in raised position, a trip for releasing said catch from the blade, a latch for retaining said trip, a contact trip member operable by the envelop and connected to said latch 120 and a swinging frame having means to restore said first trip in engagement with the latch, and means to operate said swinging re-setting member by the descent of the movable blade.

10. In an envelop opener, in combination with a vertically movable blade operable to sever a marginal strip from the envelop, power means for operating said blade, a catch for retaining said blade in inoperative position, a spring operated trip for said catch, means for permitting the operation of said trip when an envelop is inserted into the machine, a horizontally pivoted swinging frame having means to contact with said trip to re-set the latter when the frame is depressed, means carried by the blade for depressing said swinging frame and means for automatically restoring said frame to normal position.

11. In an envelop opener, in combination with a vertically movable blade, power means for operating the same, a catch for holding the blade out of operation, a blade releasing trip, a re-setting member operable by the downward movement of the blade to re-set said trip, a member connected to the blade for engaging said re-setting member,

a spring for restoring said re-setting member to normal position and buffer means adapted to cushion the return movement of said member.

12. In an envelop opener, in combination with a fixed blade, a vertically movable blade, power means for operating said movable blade, means for tripping said blade, standards in which said blade is mounted to slide, and spring guide members mounted on the edges of said blade and bearing against said standards to maintain the said edges in straight parallel lines of movement.

In witness whereof, I have hereunto set my hand and seal at Indianapolis, Marion County, Indiana this 16th day of October, 1919.

JOHN L. MCKENZIE. [L. s.]
